UNITED STATES PATENT OFFICE.

MATHIEU SOUVIELLE, OF PARIS, FRANCE.

RESPIRATOR.

SPECIFICATION forming part of Letters Patent No. 314,070, dated March 17, 1885.

Application filed December 2, 1884. (Model.)

To all whom it may concern:

Be it known that I, MATHIEU SOUVIELLE, of Paris, France, residing temporarily at Washington, in the District of Columbia, have invented new and useful Improvements in Telescopic Respirators, of which the following is a specification.

This invention relates to that class of portable or pocket respirators which are made to receive various medicaments held in absorption by a suitable packing or filling and designed to be vaporized or atomized by air drawn into the lungs through the mouth while in the act of breathing.

The object of the invention is to provide a respirator which is simple in construction, effective in operation, and can be adjusted to receive different amounts of absorbent or medicated packing, and when not in use can be placed in such position as to take up comparatively little space and firmly and safely hold the medicated packing in position within the respirator.

The invention consists in a respirator consisting of two sections or shells, one of which is open at its outer end, and is provided with curved edges, so as to fit closely around the mouth of the patient, and is provided at its other end with a foraminous or perforated head, and at some point between its ends with a circumferential bead or rib for strengthening said section and limiting the distance it can be entered into the other section. This mouth-piece portion of the respirator fits telescopically into the other section or shell, that is also provided with a perforated or foraminous end head, between which and the similar head of the mouth-piece section there is placed and retained an absorbent and medicated packing or filling of sponge, cotton, prepared tar, or other suitable material. The mouth-piece section can be moved in and out of the other section, so as to increase or diminish the size of the chamber containing the absorbent or medicated packing, whereby provision is made for tightly or safely holding such material in varying quantities, according to the requirements of the case. When the respirator is not in use, the mouth-piece section is withdrawn from the other section and placed into the latter in an inverted position, so as to

decrease the compass of the device for convenience in storage and transportation.

In the drawings, Figure 1 is a perspective view of a respirator in position for use. Fig. 2 is a perspective view representing the component sections or shells of the device in a separated state. Fig. 3 is a sectional view of the device with the absorbent or medicated packing held between two foraminous end heads of the component sections or shells. Fig. 4 represents the respirator inverted and packed in a box, with a bottle of medicated fluid designed to accompany the respirator.

The reference-numeral 1 designates one of the shell shaped sections of the respirator, which has its outer edge cut on a curved line, or is hollowed out, as is shown at 2, so as to fit closely around the mouth of the patient or user. The other section, 3, of the respirator is also made in the shape of the shell, and is designed to have the section 1 fitted into the same in either of the positions represented by Figs. 1 and 4. Both component parts of the respirator are preferably of an elliptical or oval shape in cross-section, and may be made of sheet metal, glass, celluloid, india-rubber, or other appropriate material not liable to be affected by the medicaments used in the same. The mouth-section of the respirator is formed with a circumferential bead or rib, 4, which serves to impart strength and rigidity to such section, and also limits or defines the distance said section can be entered into the other section, 2. The outer ends of both sections comprising the respirator are each provided with a foraminous or perforated end head, 5, which, when the parts are in the position shown in Fig. 3, form between them a chamber or space that is designed to receive a packing or filling of some absorbent or medicated material. I have in said figures shown said chamber when filled with several coiled strips of prepared tar and a superposed absorbent or porous packing that may be medicated by pouring on it a mixture of carbolic acid, tincture of iodine, alcohol, and water, or any other medicament or fluid the vapors of which are to be administered by passing air through the device. Thus, when decomposition of living tissues or blood-poisoning is to be arrested, carbolite of iodine is one of the essential ingredients or active agents

that can be used in the instrument by saturating or impregnating the packing placed therein. As shown in Fig. 3, the mouth-section of the device is moved sufficiently far into the other section to firmly retain the absorbent packing or medicated filling between the two foraminous end heads. When a larger amount of material is to be placed in the device, the two sections can be drawn apart in the manner of a telescope, so as to increase the size of the chamber that contains the filling.

For the purpose of properly separating different layers of packing or filling, I sometimes propose to use detachable perforated plates or foraminous diaphragms, as is shown by the dotted line 9 in Fig. 3. I may also attach rings or loops 10 to one of the sections, for receiving bands that secure the device to the head of the patient.

When the respirator is not in use, the mouth-section is withdrawn from the other section and is slipped into the same in an inverted

state, as is clearly shown in Fig. 4. The device, when in this position, takes up comparatively little room, and the curved mouth-rim is inclosed and protected and prevented from becoming bent or injured, as is readily apparent.

Having thus described my invention, what I claim is—

The herein-described respirator, consisting of the mouth section or shell having a perforated end head, a circumferential bead, and a curved rim adapted to fit the mouth of the user, and a larger shell provided with a perforated end head, and adapted to have either end of the mouth-section entered therein telescopically, substantially as described.

In testimony whereof I affix my signature in presence of two witnesses.

MATHIEU SOUVIELLE.
